UNITED STATES PATENT OFFICE

151,792

DESIGN FOR A DRILL SHARPENER

Roger P. Smith, Madison, Conn., assignor to General Hardware Mfg. Co. Inc., New York, N. Y., a corporation of New York

Application October 8, 1946, Serial No. 133,821

Term of patent 14 years

(Cl. D37—1)

To all whom it may concern:

Be it known that I, Roger P. Smith, a citizen of the United States and a resident of the city of Madison, county of New Haven, State of Connecticut, have invented a new, original, and ornamental Design for a Drill Sharpener, of which the following is a specification, reference being had to the accompanying drawings, forming part thereof, wherein Fig. 1 is a front perspective view of a drill sharpener, embodying my new design, and Fig. 2 is a similar rear view thereof.

I claim:

The ornamental design for a drill sharpener, substantially as shown.

ROGER P. SMITH.
